FOLDING TABLE AND LEG ACTUATOR

Edwin F. Knowles, Miami, Ariz.

Application July 26, 1949, Serial No. 106,882

1 Claim. (Cl. 311—82)

1

This invention relates to a folding table, particularly of the card table type, and has for one of its objects the production of a simple and efficient leg actuating means for facilitating the moving of the table supporting legs in unison to an open or folded position.

A further object of this invention is the production of a simple and efficient means for attaching the legs to an actuating ring in a manner whereby the swinging of one leg of the table to and from a folded position will automatically move the other legs to similar positions.

In the drawings:

Figure 1 is a bottom plan view of the table showing the legs thereof in an extended position;

Figure 2 is a fragmentary bottom plan view of the table showing the legs in a folded position;

Figure 3 is a fragmentary vertical sectional view of the table showing one leg in a set-up or vertical position;

Figure 4 is an enlarged fragmentary sectional view taken on line 4—4 of Figure 1;

Figure 5 is an enlarged sectional view taken on line 5—5 of Figure 1;

Figure 6 is a perspective view of one of the ring guiding frames;

Figure 7 is a fragmentary inverted perspective view of one corner of the table showing one leg in an extended position, and illustrating a portion of the actuating ring, a portion of a ring guiding frame, and the leg braces;

Figure 8 is an enlarged fragmentary sectional view taken on line 8—8 of Figure 1;

Figure 9 is a fragmentary bottom plan view of a portion of the actuating ring showing one of the leg actuating link connections.

By referring to the drawings, it will be seen that 10 designates the table top or body having side rails 11 which depend from the side edges of the body 10, as shown. A leg 12 is hingedly secured at each corner of the body 10 upon a journal bar 13 which has one end thereof journaled in the box-like portion 14 carried at one end of one of the actuating ring guiding frames. Each journal bar 13 is provided with an angle brace 15 which is integral at its inner end with the bar 13 and is inclined toward the leg 12. The opposite end 16 is journaled to the leg 12 by means of a pin 17 which also pivotally anchors the end 18 of the link rod 19 to the leg 12. The opposite end 20 of the link rod 19 is pivotally connected to an angularly extending terminal 21 of the rotatable connecting pin 22 which extends outwardly and radially of the actuating ring 23, shown in detail in Figure 9. The pin 22 is pref-

2

erably threaded transversely of the ring 23 so as to freely rotate as the actuating link 19 moves to different angular positions, which is caused by the leg 12 moving to and from an open and folded position.

As shown, a leg 12 is carried at each corner of the body 10, and a ring guiding frame 24 extends diagonally of each corner at an approximately 45 degree angle. The frames 24 are fixed to the under face of the body 10, as shown in Figure 1. Each frame 24 is preferably formed from sheet metal and is bent to provide the box-like journal 14 at one end which extends rearwardly of the frame 24 and is anchored to one side rail 11, as shown. The frame 24 is provided with end anchoring flanges 25 and 26 which are fixed to adjacent right-angularly extending side rails 11 to hold the frame at an approximate 45 degree angle. The outer face of each frame 24 is curved 15 as at 27, to conform to the circular actuating ring 23. The frame 24 is of a channel type structure and carries a pair of spaced concave ring engaging rollers 28, one roller being carried near each end of each frame. There are four frames 20 24, one in each corner of the table, and two rollers for each frame which engage the ring 23 which is preferably tubular in cross-section, as shown. These rollers 28 will firmly hold the ring 23 against accidental or forced displacement and 25 permit the ring to be easily shifted circumferentially as one leg 12 is swung, as shown in Figure 8. It should be noted that the manual operation of one leg will exert a pulling pressure on the link 19 and upon the pin 22 and this action in turn through the movement of the ring 23 creates a pushing pressure on the link 19 and upon the pin 22 and this action in turn through the movement of the ring 23 creates a pushing pressure on the pins 22 and links 19 of the other three legs 30 due to the fact that the links 19 are connected to the angularly extending terminals 21 of the pins 22, which pins 22 are rotatably connected to the ring 23 and extend radially and outwardly of the ring 23. This arrangement prevents binding of the parts during operation and causes the other legs to freely and simultaneously swing as one leg 35 is manually swung by the operator.

It should be understood that the concave spaced rollers 28 of one frame 24 are located 40 in diametrically opposed relation to the spaced rollers 28 of the diametrically opposed frame 24 so as to firmly hold the ring 23 in rotatable frictional contact with all of the rollers and against accidental displacement from the rollers. As is 45 shown in Figure 3, the ring 23 is in a horizontal 50

plane which is inset toward the table top 10 relative to the horizontal plane of the journal bar 13, and the outer end or crank end 21 of the radiating pin 22 extends inwardly toward the table top 10. Consequently, as the ring 23 is rotated by pulling one leg 12 outwardly the pins 22 will produce an outward thrusting action upon the links 19 and the links 19 will in turn have an outward thrusting action upon their companion legs to swing all of the legs in unison to an open position.

One of the frames 24 is provided with a pair of spaced locking pins 29 and 30 to be engaged by an apertured spring latching plate or latch 31 which is carried by the actuating ring 23. A stop or abutment 32 is located near the locking pin 29 against which the latch 31 abuts to brace the latch 31 when the legs 12 are in an open position.

From the foregoing description it will be seen that as one leg 12 is swung from an extended position to a folded position after the latch 31 has been released, the actuating ring 23 will be rotated, thereby simultaneously moving the remaining legs to a like position. This operation is due to the fact that the link rods 19 connect the legs 12 to the ring 23. A simple and efficient structure thereby is provided to facilitate the swinging of the legs 12 to and from an extended position and also for holding the legs in such positions until the latch 31 is automatically released as a slight additional pressure is applied to the leg 12, which is being swung by the operator.

It should be understood that certain detail changes may be made in the detail structure and design without departing from the spirit of the invention, so long as these changes fall within the scope of the appended claim.

Having described the invention, what is claimed as new is:

A device of the class described comprising a table top having side rails depending from the side edges thereof, an actuating ring guiding frame extending diagonally across each corner of the table top and engaging the side rails adjacent the corners of the table top to brace said rails, a leg carried at each corner of said table top, a journal bar for hingedly connecting each leg to said table top, each journal bar being journaled at one end in one side rail and journaled at its opposite end to one of said frames, a brace connected to each journal and also connected to the adjacent leg, an actuating link pivotally connected to each leg, a circular actuating ring mounted between said guiding frames and located in a horizontal plane inwardly toward the table top relative to the journal bars of said legs, means carried by said frames for retaining the ring between the frames, crank pins extending outwardly and radially of said rings, and each crank pin having an inturned end extending toward the table top and engaging the adjacent actuating link to produce an outward thrust upon the legs and the actuating links as the ring rotates to thereby open the legs in unison as one leg is swung outwardly.
